SPARK PLUG AND IGNITION WIRE
ATTACHMENT MEANS

Francis E. Berstler, Middletown, Pa., assignor of
thirty-three and one-third per cent to Charles
V. Hoke, Hummelstown, and thirty-three and
one-third per cent to Ezra O. Brubaker, Eliza-
bethtown, Pa.

Application November 27, 1950, Serial No. 197,696

1 Claim. (Cl. 123—169)

1

This invention relates generally to spark plugs and more particularly to a spark plug wherein the center electrode is adjustable in an axial direction and wherein special means is provided for the attachment of the current conductor or lead wire.

A primary object of this invention is to provide a spark plug allowing adjustment of the center electrode longitudinally of itself during actual operation of the motor, with the corresponding cylinder firing, along with one or more other cylinders in order to allow the motor to function, this feature being concerned with the attainment of perfect adjustment for the compression pressure of that particular cylinder.

Another object of this invention is to provide a novel and improved means for securing an ignition wire to a spark plug.

Another object of this invention is to provide a spark plug which will not readily become fouled, and wherein certain parts can be removed periodically for cleaning purposes.

Yet another object of this invention is to provide a spark plug wherein certain parts, more likely than others to become damaged, can be easily replaced.

A last object to be mentioned is to provide a spark plug which is relatively simple and practicable to manufacture, the different parts being each simple in themselves and capable of mass production at low cost, and to provide a spark plug which is generally efficient in operation.

With the above objects definitely in view, this invention resides in certain novel features of construction, combination and arrangement of elements and portions as will be hereinafter described in detail in the specification, particularly pointed out in the appended claim, and illustrated in the accompanying drawing wherein:

Figure 1 is a side elevational view of a spark plug, the figure including representation of a portion of an ignition or lead wire, and a portion of a cylinder block, the latter being in vertical cross section;

Figure 2 is a vertical cross sectional view of the spark plug, the view being taken substantially on the line 2—2 in Figure 4;

Figure 3 is a lower end elevational view of the spark plug;

Figure 4 is a horizontal sectional view taken substantially on the line 4—4 in Figure 2; and

Figure 5 is a horizontal sectional view taken on the line 5—5 in Figure 2.

Similar characters of reference designate similar or identical elements and portions throughout

2

the specification and throughout the different views in the drawing.

Referring now to the drawing in detail, this spark plug includes a body 10, which is generally tubular, the externally threaded portion 12 of the body being adapted for being screwed into a cylinder block fragmentarily illustrated at 14. The center portion of the body 10 is enlarged as indicated at 16 and a plurality of circumferentially spaced cylindrical recesses 18 are provided therein to receive a wrench, whereby the body 10 may be screwed into the cylinder block 14. The end of the body 10 adjacent the threaded portion 12 is provided with a plurality of inwardly turned fixed electrodes 20, these fixed electrodes being preferably integral with the body 10. The latter body is preferably constructed of stainless steel or stellite, and in any case, it is important that the electrodes 20 be constructed of one of these substantially non-magnetic substances or an equivalent substance. The body 10 is also provided with an internal, axially projecting flange 22, and the internal diameter of the body 10 is increased in that portion of the body remote from the fixed electrodes 20.

A sleeve 24 is constructed of a substance which is electrically non-conductive, this sleeve having an enlarged intermediate portion 26 terminating in an axially projecting annular flange 28 which fits reasonably snugly into this space between the annular flange 22 of the body 10 and the adjacent portion of said body. An end portion 30 of the sleeve 24 extends beyond the annular flange 28, into that portion of the body which is threaded as at 12, and the said end portion 30 of the insulative sleeve is coextensive with the threaded portion. A gasket 32 is compressed between the end of the annular flange 28 and the adjacent portions of the body 10.

A nut 34, externally threaded at 36, is screwed into a correspondingly threaded end portion of the body 10 remote from the fixed electrodes 20, and another gasket 38 is compressed between the threaded end portion 36 of the nut 34 and the enlarged intermediate portion 26 of the sleeve 24, this construction holding the sleeve 24 in place on the body 10, all as will be clearly understood from an inspection of Figure 2. The nut 34 has an enlarged intermediate portion 40 which is provided with a plurality of circumferentially spaced wrench receiving apertures 42.

A metal tube 44 extends the full length of the sleeve 24 and is bonded internally thereto, the outer surface of the tube 44 being roughened to improve such bonding, and the sleeve 24 being

ordinarily molded directly upon the tube 44. The tube 44 has a portion extending beyond that end of the sleeve 24 remote from the fixed electrodes 20.

An adjustable electrode 46 comprises a metal bar, externally threaded, and provided at one end with a plain cylindrical element 48, this element 48 being preferably of stainless steel or stellite, and it is preferred that the element 48 be integral with the main portion of the adjustable electrode or rod 46. The end of the adjustable electrode 46, remote from the element 48 is provided with a kerf 50, to facilitate adjustment of the electrode.

An externally and internally threaded tubular member 52 is threaded on that portion of the tube 44 extending beyond the end of the sleeve 24, a kerf 54 being provided in one end of this member 52 to allow the member 52 to be screwed onto the said extending portion of the tube 44, and a cap 56, provided with a kerf 58, is used to close the outer end of the member 52. Of course, the member 52 extends beyond that end of the adjustable electrode 46 remote from the fixed electrodes 20. The member 52 is provided with a plurality of circumferentially spaced apertures 60.

The member 52, described immediately above, comprises a part of the means for attachment of a terminal 64 of an ignition wire. This terminal is provided with a reduced neck portion 66. A nut 62 is threaded on the member 52 and this nut is provided with an annular flange 68. A coacting nut 70 having a similar flange 72 is disposed on the other side of the terminal 64, the flanges 68 and 72 engaging the reduced portion 66 and holding the terminal rigidly in place, while providing for good electrical contact between the terminal and the tube 44 and adjustable electrode 46.

The operation of this invention will be clearly understood from the foregoing description of the mechanical details thereof, taken in connection with the drawing and the above recited objects. In recapitulation, it need only be added that the screw cap 56 is removed to provide access to the adjustable electrode 46, for adjustment thereof during the actual operation of the motor. Since the apertures 60 are circumferentially spaced at equidistant points, the terminal 64 is selectively inserted in one of these apertures, thus facilitating the most convenient arrangement and connection of the ignition wire. It will be clear that each of the objects mentioned in an early part of this specification is achieved fully by this invention.

Having described the invention, what is claimed as new is:

For use in conjunction with a spark plug insu-

5 lator and electrode assembly embodying a sleeve of dielectric material, a metal tube fitting into the bore of said sleeve and bonded to the latter and constituting a bushing and having its axial passage internally screw-threaded and having one end projecting beyond the corresponding end of said sleeve and provided with external screw-threads, and a screw-threaded electrode screwed into and through the internally screw-threaded passage of said tube and having an upper end projecting beyond the upper end of said tube; terminal connector means adapted for detachable cooperation with said electrode comprising a tubular member having internal and external screw-threads, said tubular member being adapted to be removably screwed on the projecting end of said tube with its lower end abutting the upper end of said sleeve and with its upper end projecting beyond the corresponding end of said tube as well as the corresponding end of said electrode and serving to enclose and protectively house the upper end of said electrode, said tubular member being provided intermediate its upper and lower ends with equidistant circumferentially spaced apertures to selectively receive a conformably shaped terminal on a current conductive lead wire, the upper end of said tubular member being provided with a screw driver kerf, a plug removably secured in and closing the upper end of said tubular member, a current conductive lead wire having a terminal embodying a portion conformably and removably fitted into a selected one of said apertures, and means removably mounted on the external screw threads on said tubular member and directly coacting with said terminal to prevent accidental displacement of the same from the aperture in which it is located, said means comprising a pair of nuts removably screwed on said tubular member at longitudinally spaced points and located on diametrically opposite sides of said terminals, said terminal having a reduced neck portion and the opposed coacting faces of said nuts having endless flanges with portions thereof fitting against and engaging said neck portion.

FRANCIS E. BERSTLER.
